UNITED STATES PATENT OFFICE

OSCAR C. PIERCE, OF OAKLAND, CALIFORNIA

DESIGN FOR AN ILLUSORY DISPLAY DEVICE

Application filed October 6, 1931. Serial No. 41,320. Term of patent 7 years.

To all whom it may concern:

Be it known that I, OSCAR C. PIERCE, a citizen of the United States, and a resident of Oakland, in the county of Alameda and State of California, have invented a new, original, and ornamental Design for an Illusory Display Device, of which the following is a specification, reference being had to the accompanying drawings, forming part thereof.

Figure 1 is a perspective view of an illu-

sory display device embodying my new design.

Figure 2 is a fragmentary sectional elevation through the device 2—2 in Figure 1, being illustrated to a somewhat larger scale.

I claim:

The ornamental design for an illusory display device substantially as shown.

OSCAR C. PIERCE.
